FUEL INJECTION PUMP

Herbert C. Edwards, Massillon, Ohio, assignor to
 The Timken Roller Bearing Company, Canton,
 Ohio, a corporation of Ohio

Application March 25, 1936, Serial No. 70,805

7 Claims. (Cl. 103—154)

This invention relates principally to fuel injection pumps of the kind having tappet actuated pistons. It has for its principal object to provide simple, efficient and easily operable means for axially adjusting the piston to take up wear of the parts and to obtain a proper initial setting of the pistons. The invention consists in the construction, combinations and arrangements of parts hereinafter described and claimed.

In the accompanying drawings, which form part of this specification and wherein like symbols refer to like parts wherever they occur,

Fig. 1 is a vertical central section through a cylinder of a fuel injection pump embodying my invention.

Fig. 2 is an enlarged fragmentary section through the pump in the region of the tappet mechanism.

Figs. 3, 4 and 5 are horizontal sections on the lines 3—3, 4—4 and 5—5, respectively, in Fig. 2,

Fig. 6 is a vertical section on the line 6—6 in Fig. 2,

Figs. 7 and 8 are sections similar to Figs. 2 and 6, respectively, illustrating a modified form of the invention; and

Figs. 9 and 10 are sections similar to Figs. 7 and 8, respectively, illustrating another modified form of the invention.

In the accompanying drawings, my invention is shown in connection with a fuel injection pump comprising a housing 1 provided with one or more vertical bores 2, each having an enlarged lower end portion 2a adapted to slidably receive a tappet cup 3 that is engaged at its lower end by a cam or tappet 4 on a shaft 5 located in a chamber 6 in the bottom of said housing. A pump cylinder 7, which contains a piston or plunger 8, has an enlarged upper end portion 9 that is held down on an annular seat 10 provided therefor in the upper portion of the bore 2 by means of a cylindrical shell 11 threaded into the upper end thereof.

Mounted on the upper end of the cylinder is a tubular member 12 that is provided at its upper end with a seat for a suitable discharge valve 13. Threaded into the upper end of the bore 2 is a tubular fitting or shell 11, which holds the valve seat on the pump cylinder and is provided in its upper end with a coil spring 15 that normally holds the fuel discharge valve 13 against its seat. A fuel discharge pipe 16 has a conical end portion seated in a beveled seat provided therefor in the upper end of the fitting 14 and

held in position by means of a cap 17 threaded on the upper end of said tubular fitting.

Inlet and overflow passageways 18 and 19 are located in the pump housing 1 on opposite sides of the cylinder 7. The inlet passageway 18 is supplied with liquid fuel by the usual feed pump (not shown) and communicates with an inlet port 18a in the wall of said cylinder. The overflow or by-pass passageway 19 communicates with an overflow port 19a in said cylinder opposite the inlet port 18a therein. The piston 8 is provided with an annular groove 20 that communicates with a longitudinal peripheral groove 21 with the pressure space above the piston, whereby delivery of the fuel begins as soon as the piston on its way up covers the ports 18a and 19a and ends as soon as the annular groove 20 in the piston is placed in communication with the overflow or by-pass port 19a and relieves the pressure in the space above the piston. The annular groove 20 in the piston has an inclined or helical upper edge 22, whereby the quantity of fuel delivered may be regulated by turning the piston in its cylinder to vary the point in the delivery stroke of the piston in which the overflow port 19a is placed in communication with said pressure space through the grooves 20 and 21.

The mechanism for turning the reciprocating plunger or piston on its axis comprises axially aligned upper and lower driving and driven sleeves 23 and 24 mounted on the lower end portions of the cylinder 7 and piston 8, respectively, and a control rod 25 mounted in a horizontal bore in the pump housing and provided with rack teeth 30 that cooperate with a gear 27 formed on the upper end of said upper or driving sleeve. The upper or driving sleeve 23 is rotatably mounted on the lower end of the cylinder 7; and the lower or driven sleeve 24 has a driving connection with the lower end of the piston comprising a flat-sided portion 28 on the piston that fits within a similarly shaped opening in the lower end of said lower or driven sleeve. The driving connection between the driving sleeve 23 and the driven sleeve 24 preferably comprises upwardly extending tongues 29 on the driven sleeve that fit within downwardly opening notches 30 in the driving sleeve, thereby permitting relative axial movement of the two sleeves but preventing relative rotary movement thereof.

Surrounding the driving and driven sleeves 23 and 24 is a helical compression spring 31 that serves to retract the piston and to hold the driving sleeve upwardly in the enlarged portion 2a 55

of the vertical bore 2 in the pump housing 1. The tappet cup 3 surrounds the driven sleeve 24 but is spaced therefrom far enough to accommodate the spring 31. A washer 32 surrounds and supports the driving sleeve 23 below the gear 27 thereon and is held against the underside of an annular shoulder in said bore by means of the spring 31. The piston is provided below its squared driven sleeve engaging portion 28 with an annular groove 33, above said portion with a collar 34, and terminates below said groove in a squared portion 35 similar to the squared portion 28. The piston retracting spring 31 is seated on the peripheral flange 36a provided 10 on a member 36 that is provided with a laterally opening notch 37 whose upper end fits the annular groove 33 in the piston and whose lower end is widened to accommodate the squared portion 35 of said piston. By this arrangement, 15 relative axial movement of the spring seat 36 and the piston is prevented; and said spring seat cooperates with the collar 34 on said piston to prevent movement on the driven sleeve 24 axially thereof.

20 25 The spring seat or collar 36 is provided on its under side with an undercut diametral groove or channel 38 adapted to receive a block 39 having outstanding ribs or flanges 39a along its upper side corners that fit the undercut portions 30 of said groove or channel. The block 39 rests on the bottom of the tappet cup 3 and is inserted in and removed from the groove 38 in the spring seat member 36 through an opening 40 provided therefor in the side wall of said cup. As 35 shown in Figs. 1 and 2, the adjusting block 39 has a raised middle portion 39b that fits within the lower end of the spring 31, thereby retaining said block in the groove 38 in the spring seat member 36. The side wall of the pump housing 40 1 is also provided opposite the opening 40 in the side wall of the tappet cup with an opening 41 through which the block 39 may be inserted and removed, the opening 41 being closed by a threaded plug 42. By this arrangement, a 45 proper initial axial adjustment of the plunger may be obtained and wear of the tappet mechanism taken up by inserting a block 39 of proper thickness in the groove 38 in the underside of the spring seat member 37. The adjusting block 50 39 is preferably provided with a threaded bore 43 that extends therethrough from end to end thereof; and said block is removed from and inserted in the spring seat member through the openings 41 and 40 in the pump housing 1 and tappet cup 3, respectively, by threading the end 55 of a rod (not shown) into one end of the threaded bore 43 in said block. The tappet cup is provided below the spring seat member with an interior shoulder 3a which forms a stop for 60 preventing said member from dropping into the space required for the adjusting block.

65 In the modification shown in Figs. 7 and 8, the adjusting block is in the form of a cylindrical disk 44 that seats within a circular depression provided therefor in the bottom of the tappet cup and is provided with a threaded diametral bore 45 having a pin 46 projecting from one end thereof into a hole 47 provided therefor in the cylindrical wall of said tappet cup. The pin 46 serves to prevent rotation of the adjusting block relative to the tappet cup. The adjusting block is inserted and removed through openings 48 and 49 provided therefor in the tappet cup and pump housing, respectively, by means of a

pin (not shown) that is threaded into the open end of the threaded bore 45 in said block.

In the modification shown in Figs. 9 and 10, the tappet adjusting mechanism comprises an inverted channel-shaped member 50 mounted in the tappet cup below the spring seat member, which has a hardened steel button 36a seated in its underside provided with a convex head that bears upon the top of said channel shaped member. Said member is provided at the lower edges of its side walls with outstanding flanges that serve to locate said member centrally within the tappet cup. The undersurface of the top wall of the channel shaped member converges downwardly from its ends to its middle; and blocks 51 are located within said channel shaped member and have inclined opposing end surfaces or planes adapted to engage the inclined undersides of said member. A screw 52 extends through axially aligned holes provided therefor in the wedge blocks and is provided at its ends with slots for a screw driver. The screw 52 extends loosely through the hole in one wedge block and is threaded through the hole in the other wedge block and is provided with a collar 53 that bears against the outer end of said first mentioned block. One end of the adjusting screw fits within one of a pair of diametrically opposed holes 54 in the tappet cup, thereby preventing rotary movement of the adjusting device in the tappet cup. The pump housing is provided at the level of the holes 54 with an opening 55 whereby access may be had to the adjusting screw 52 to draw the wedge blocks together or force them apart and thus raise or lower the piston.

What I claim is:

1. A fuel injection pump comprising a housing, a piston reciprocable in said housing, a tappet cup reciprocable and rotatable in said housing and surrounding one end of said piston, a tappet for actuating said tappet cup, and means interposed between said piston and the bottom of said tappet cup for axially adjusting said piston, said tappet cup and said housing having side openings therein adapted to be brought into register and through which said means is adapted to be inserted in and removed from said tappet cup and said housing.

2. A fuel injection pump comprising a housing, 50
a piston reciprocable in said housing, a tappet cup surrounding one end of said piston, a tappet for actuating said tappet cup, a member secured to said end of said piston against movement axially thereof and for engagement with and disengagement from said piston transversely thereof, and a second member interposed between said removable member and the bottom of said tappet cup, said tappet cup and said housing having cooperating side openings therein through which said second member is adapted to be inserted in and removed from said tappet cup and said housing. 60 65

3. A fuel injection pump comprising a housing, a piston reciprocable in said housing, a tappet cup surrounding one end of said piston, a tappet for actuating said tappet cup, a member removably secured to said end of said piston against movement axially thereof and for engagement with and disengagement from said piston transversely thereof, a member interposed between said removable member and the bottom of said tappet cup, said tappet cup and said housing having cooperating side openings therein through which said second mentioned mem-

ber is adapted to be inserted in and removed from said tappet cup and said housing, said tappet cup being provided with an internal shoulder adapted to space said first mentioned member away from the bottom of said cup when said second mentioned member is removed from said cup.

4. A fuel injection pump comprising a housing, a piston reciprocable in said housing, a tappet cup surrounding the lower end of said piston, a tappet for actuating said tappet cup, a spring seat member secured to said end of said piston and having a cross groove in the under side thereof, and a member mounted in said groove 15 and bearing against the bottom of said tappet cup, said tappet cup and housing having cooperating openings therein through which said member may be inserted in and removed from the cross groove in said spring seat member.

5. A fuel injection pump comprising a housing, a piston reciprocable in said housing, a tappet cup surrounding the lower end of said piston, a tappet for actuating said tappet cup, a spring support secured to said end of said piston and 25 having an undercut diametral groove in its bottom, and an adjusting block slidably mounted in said groove, said tappet cup and said housing having openings therein through which said block may be inserted and removed from said 30 pump, said block having an opening in one end thereof adapted to receive a member for facilitating such insertion and removal of said block.

6. A fuel injection pump comprising a housing, a piston reciprocable in said housing, a tappet cup surrounding the lower end of said piston, a tappet for actuating said tappet cup, a spring seat member removably secured to said end of 35 said piston, an adjusting block interposed between said member and the bottom of said tappet

cup, said tappet cup being provided opposite said block with diametrically opposed openings, and a pin secured to said block and extending into one of said openings, said housing having an opening adapted to cooperate with the other of said diametrically opposed openings, said block being adapted to be inserted in and removed from said tappet cup and said housing through said cooperating openings and having an opening 5 that is held by said pin in register with said other of said diametrically opposed openings and is adapted to receive a member for facilitating such insertion and removal of said block through said cooperating openings.

7. A fuel injection pump comprising a housing, 15 a piston reciprocable in said housing, a tappet cup surrounding the lower end of said piston, a tappet for actuating said tappet cup, a spring seat member removably secured to said end of said piston, an adjusting block interposed between said member and the bottom of said tappet cup, said tappet cup being provided opposite said block with diametrically opposed openings, and a pin secured to said block and extending into one of said openings, said housing having an 20 opening adapted to cooperate with the other of said diametrically opposed openings, said block being adapted to be inserted in and removed from said tappet cup and said housing through said cooperating openings and having an opening 25 that is held by said pin in register with said other of said diametrically opposed openings and is adapted to receive a member for facilitating the insertion and removal of said block through said 30 cooperating openings, said tappet cup being provided with an internal shoulder adapted to limit the movement of said spring seat towards the bottom of said tappet cup.

HERBERT C. EDWARDS.
